DESIGN FOR A TURBOSUPERCHARGER

Nathan C. Price, Hollywood, Calif.

Application November 8, 1940, Serial No. 96,441

Term of patent 7 years

To all whom it may concern:

Be it known that I, Nathan C. Price, a citizen of the United States, residing at Hollywood, in the county of Los Angeles and State of California, have invented a new, original, and ornamental Design for Turbosuperchargers, of which the following is a specification, reference being had to the accompanying drawings, forming part thereof.

Figure 1 is a side elevational view of a turbosupercharger, showing my new design.

Figure 2 is a plan view of the turbosupercharger shown in Figure 1.

Figure 3 is a view of the turbosupercharger in the side elevation opposite to that shown in Figure 1.

I claim:

The ornamental design for a turbosupercharger, as shown.

NATHAN C. PRICE.
